CABLE CONNECTOR

Robert A. Sharp, Milwaukee, Wis.

Application June 27, 1951, Serial No. 233,839

1 Claim. (Cl. 339—274)

1 This invention relates to couplers or connectors for electrical conductors such as cables, and has particular reference to a coupling for connecting the leads of welding equipment.

It is customary to secure the coupling members for such leads to the conductor wires or cables by soldering the ends of the cables into sockets in the coupling members. This practice, of course, requires that the connection between the complementary coupling members themselves be of low electrical resistance so as to avoid heating of the coupling members.

Heretofore, however, the means employed to effect a separable connection between the complementary coupling members was incapable of achieving the necessary degree of low electrical resistance, and as a result, the solder securing the conductors to the coupling members often melted or softened to the extent that a failure would occur.

With a view toward correcting this specific problem it is the purpose of the present invention to provide a new and improved coupler for electric conductors wherein the connection between the coupling members extends over a substantial area and is so tight and secure as to prevent substantially all heating due to electrical resistance at the junction.

Another object of this invention is to provide a coupler for the purpose described wherein the coupling or connection between the coupling elements is quickly and easily effected by merely sliding complementary interengaging portions thereof axially onto one another and then rotating the coupling members with respect to each other.

A further object of this invention is to provide an electrical coupler of the character described wherein one of the coupling members has an annular wall which is wedged between and clamped by a pair of cooperating elements on the other coupling member, to thereby afford a secure mechanical connection between the members and a good electrical contact between their clamped parts.

With the above and other objects in view, which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claim.

The accompanying drawing illustrates one

2 complete example of the physical embodiment of the invention constructed according to the best mode so far devised for the practical application of the principles thereof, and in which:

5 Figure 1 is a perspective view of the two complementary coupling members of this invention shown separated and attached to the ends of the conductors which are to be electrically connected;

10 Figure 2 is a longitudinal sectional view through the coupler with the complementary members thereof in engagement with one another;

15 Figure 3 is an enlarged cross-sectional view taken along the line 3—3 of Figure 2 and illustrating the two complementary coupling members in their positions of relative rotation at which assembly and disassembly is effected; and

20 Figure 3A is a view similar to Figure 3 but showing the coupling members rotated with respect to each other to establish a secure low resistance connection therebetween.

25 Referring now particularly to the accompanying drawing, the numerals 5 and 6 designate generally the two complementary coupling members of this invention, each of which has a socket 7 opening to one end thereof to receive and have the end portion of a conductor 8 soldered therein.

30 Though the coupling members may be cast or formed in any desired manner, in the present instance they are illustrated as being turned from hexagonal bar stock. The member 5 has a coaxial smooth surfaced cylindrical bore 9 therein opening to its end opposite its socket 7, and a smooth surfaced cylindrical pin 10 smaller in diameter than the bore 9 is disposed therein to be encircled by the skirt 11 defined by the bore 9.

35 Where the member is formed of hexagonal bar stock, as in the present case, the pin 10 is a separate part driven into a central bore 12 opening to the bottom of the bore 9. The bore 12 is so disposed as to locate the pin 10 with its axis parallel to but spaced a slight distance from the axis of the bore 9, as indicated by the dimension "S" in Figure 3. Consequently the bore 9 and the pin 10 are slightly eccentric to one another.

40 The other coupling member 6 has a smooth surfaced tubular stem 13 projecting from the end thereof opposite its socket 7, and the inner and outer diameters of this tubular stem are eccentric to the same extent as the bore 9 and pin 10. Also, the outer diameter of the stem 13, while coaxial with the member 6, is slightly less than

the diameter of the bore 9; and its inner diameter is slightly greater than the diameter of the pin 10. Consequently, when the two coupling members are axially aligned with one another and in such positions of rotation that the eccentricities of their parts coincide, they may be freely slid axially into interengagement with the skirt 11 surrounding the tubular stem 13 and with the tubular stem surrounding the pin 10. Upon being so interengaged, rotation of one of the elements with respect to the other produces a double wedging effect which takes place between the inner and outer surfaces of the tubular stem 13 and the skirt 11 and pin 10, and by this double wedge action the telescoped parts are securely locked together.

While the radially adjacent cylindrical surfaces of the connected coupling members have a theoretical line contact with one another when rotated into locking engagement, as a practical matter the inevitable resiliency and elasticity of the interengaged parts brings about a substantial surface-to-surface engagement between the two members to thereby effect a good electrical connection therebetween.

Since the interengaged parts must have a rather snug fit, the inner end of the tubular stem 13 has a small diameter bleed hole 14 through the wall thereof to thus preclude entrapment of air in its interior when the members are slid together; and a similar bleed hole 15 is provided in the wall of the member 5 just ahead of the inner end of the bore 9 for the same purpose.

The exposed end of each coupling member is enclosed in a sheath 16 of suitable insulating material, and these insulating sheaths are brought substantially into endwise abutting relationship when the members are interconnected.

Attention is directed to the fact that the relative positions of rotation of the two coupling members is effectively indicated by screws 17, one threaded into each of the members, and visible through holes 18 in the sheaths. The screws are so located circumferentially of the two members that when the same are in their assembling and disassembling positions at which their eccentricities match, as shown in Figure 3, the screws are exactly aligned with one another, lengthwise of the coupler. Hence, the screws 17 facilitate quick connection. If desired, the screw 17 in the member 5 may extend far enough inwardly as to engage in a hole 19 in the side of the pin 10 to hold the same against endwise displacement. The engagement of the heads of the screws 17 in the holes 18 of the sheaths also

5 serves to preclude axial displacement of the sheaths from their respective members.

From the foregoing description taken in connection with the accompanying drawing, it will be readily apparent to those skilled in the art that this invention provides a very low resistance coupler for cables and other electrical conductors.

What I claim as my invention is:

4 A coupler for electric conductors, comprising: 10 a pair of complementary elongated coupling members each of which has a socket opening to one end to receive and have an end portion of a conductor soldered therein, one of said coupling members having a complete smooth-surfaced substantially uniform cylindrical bore extending axially thereof and opening to its end opposite its socket to define a skirt, and also having a smooth-surfaced substantially uniform cylindrical pin wholly within the skirt bore with its outer end substantially in line with the edge of the skirt but the pin being slightly eccentric to the skirt; and a smooth-surfaced substantially uniform cylindrical tubular stem 15 extending axially of the other member and projecting from its end opposite its conductor socket, the inside and outside surfaces of said tubular stem having the same eccentricity as the pin and skirt bore, and the relative diameters of said parts being such that the tubular stem may be 20 freely slidably telescoped into the skirt bore and over the pin of the first designated coupling member when said coupling members are in predetermined positions of relative rotation at which their eccentricities substantially coincide, and 25 whereby relative rotation of said coupling members in either direction, with their parts thus telescoped and mating, locks them together by the double wedging action which takes place 30 between the surfaces of the tubular stem and those of the pin and skirt, to form a low resistance electrical connection between the coupling members which extends along the entire axial length 35 of the contacting surfaces and increases the intimacy and area as the coupling is tightened 40 by relative rotation of its mating members.
